UNITED STATES PATENT OFFICE.

JOHN A. CAULKINS, OF HARTFORD, CONNECTICUT.

LANDING-STAGE FOR AEROPLANES.

1,340,325.

Specification of Letters Patent.

Patented May 18, 1920.

Application filed May 10, 1918. Serial No. 296,198.

To all whom it may concern:

Be it known that I, JOHN A. CAULKINS, a citizen of the United States, residing at Hartford, in the county of Hartford and State of Connecticut, have invented a new and useful Improvement in Landing-Stages for Aeroplanes, of which the following is a specification.

This invention relates to the construction of means which will provide suitable landing and launching stages for aeroplanes in cities, towns, and closely built communities where there are no open fields of sufficient size, and in open country where the fields are too broken and uneven to be used for landing and launching with safety.

The object of the invention is to provide a structure which will be sufficiently strong, firm and yet not too rigid to permit the satisfactory and safe landing and launching of aeroplanes and sustain the combined weight of the machines and accompanying pilots, mechanics and passengers, and will be so open or skeleton-like that it will be light in weight, will shut out daylight to a comparatively small degree, and will offer but minimum resistance to the elements—rain, snow, ice and wind—thereby enabling it to be cheaply erected over buildings in cities without such disadvantages as would render it impracticable.

Figure 1 of the accompanying drawings shows a perspective view of a landing and launching stage which embodies the invention illustrated as erected over a section of a city. Fig. 2 shows on a larger scale a vertical section of a portion of the structure taken on the plane indicated by the line 2 on Fig. 3. Fig. 3 shows a plan of a portion of the structure.

The preferred form of the invention which is illustrated has the necessary number of vertical latticed supporting columns 1 that may be anchored at suitable distances apart on the roofs of buildings or in the ground according to the local conditions where the structure is to be erected. These columns are desirably formed of angle-iron corners 2 united by cross bracing strips 3. Light lattice girders 4 formed of angle-iron corners 5 and oblique bracing strips 6 are secured horizontally to the tops of the supporting columns. Suspended between the girders and extending from side to side at suitable distances apart are heavy wire cables 7, and separating these cables and re-

taining them desirably spaced are light channel irons 8. The channel irons and cables are secured together by clamps 9. Upon the framework of girders, cables and channel irons thus formed and supported by the columns a flooring of extra heavy expanded metal lath 10 is secured, and over this flooring is placed a surfacing sheet of heavy gage wire screen mesh 11.

Steps 12 may be arranged where desired from the top of the landing stage to the roof of a building beneath to permit ready ascent to or descent from the landing stage.

The lattice columns and girders form a light and substantial supporting frame which can be built any height and size at comparatively low cost without obstructing traffic. The cables and channels are readily obtained and easily placed in position, and they provide a desirable yielding, yet strong, base for the flooring, while the expanded metal lath, which is a common article of commerce, forms a firm yet light flooring and the wire mesh provides a suitable covering surface for machines and people. The whole structure is relatively light in weight and is sufficiently open so that rain, snow and ice will not gather and weight it down, and so that light will be obstructed only to a minimum degree, thus enabling the structure to be erected over buildings in a city without serious inconvenience to the occupants of the buildings below or in the immediate locality. The structure may have sufficient area to provide a safe landing and launching field for aeroplanes above a single building or a group of buildings in a city and can be erected without such serious disadvantages as would prohibit its use.

The invention claimed is:—

1. A landing and launching stage for aeroplanes comprising supporting columns of suitable height, horizontally arranged girders connecting the tops of the columns, cables extending between and supported by the girders, and a reticular metallic flooring laid upon the cables and extending between the girders.

2. A landing and launching stage for aeroplanes comprising supporting columns of suitable height, horizontal girders connecting the tops of the columns, cables extending between and supported by the girders, channel irons retaining the cables spaced, and a reticular metallic flooring laid

upon the cables and channel irons and extending between the girders.

3. A landing and launching stage for aeroplanes comprising supporting columns of suitable height, horizontal girders connecting the tops of the columns, cables extending between and supported by the girders, channel irons retaining the cables spaced, expanded metal lath secured upon the cables and channel irons and extending between the girders.

4. A landing and launching stage for aeroplanes comprising supporting columns of suitable height, horizontal girders connecting the tops of the columns, cables extending between and supported by the girders, channel irons retaining the cables spaced, expanded metal lath secured upon the cables and channel irons and extending between the girders, and wire screen mesh covering the expanded metal lath.

5. A landing and launching stage for aeroplanes comprising latticed metal verti-

cal columns, latticed metal horizontal girders connecting the tops of the columns, wire 25 cables extending between and supported by the girders, channel irons retaining the cables spaced, expanded metal lath secured upon the cables and channel irons and extending between the girders, and wire 30 screen mesh covering the expanded metal lath.

6. A landing and launching stage for aeroplanes comprising supporting columns, girders connecting the tops of the columns, 35 and a firm, flexible, reticular, metallic flooring suspended between and supported by the girders.

7. A landing and launching stage for aeroplanes comprising supporting columns, 40 means connecting the tops of the columns, and a reticular metallic flooring suspended between and supported by the said connecting means and columns.

JOHN A. CAULKINS.
